UNITED STATES PATENT OFFICE.

RUDOLPH H. GLADWILL, OF ADA, OKLAHOMA, ASSIGNOR TO PATENT HOLDING COMPANY, OF ADA, OKLAHOMA, A CORPORATION OF OKLAHOMA.

CHECK-INDORSING MACHINE.

1,253,025.

Specification of Letters Patent. Patented Jan. 8, 1918.

Application filed April 5, 1917. Serial No. 159,992.

To all whom it may concern:

Be it known that I, RUDOLPH H. GLADWILL, a citizen of the United States, and resident of Ada, in the county of Pontotoc and

5 State of Oklahoma, have invented a new and Improved Check-Indorsing Machine, of which the following is a full, clear, and exact description.

10 My invention relates to a means of mechanically indorsing checks, drafts, memoranda, and the like, hereinafter referred to as checks.

15 More particularly the invention relates to an indorsing machine adapted to be used in connection with an adding machine and involving a rotary stamp and a chute arranged to receive the checks directly from a leaf corresponding with the leaf in certain adding machines on which the checks are laid.

20 Objects of the invention are to provide a check indorsing means having clamps, whereby to attach the indorsing machine to an adding machine; to provide stamping rollers so formed as to insure that the checks 25 will be gripped thereby and drawn through the rollers to receive the stamped indorsement; to provide novel spring means to resiliently maintain the rollers under an even pressure; to provide means for giving the 30 rollers a complete revolution by the movement of the crank handle of the adding machine and to provide co-acting means associated with the rollers to prevent retrograde movement thereof so that the adding machine handle may be operated normally 35 while the rollers will be given a single revolution and then arrested in their proper relative positions for receiving the check; to provide a stamping roller on which a rubber 40 stamp will be adjustably and removably mounted, whereby the stamp may be positioned to variously locate the indorsement on the check as may be necessary; and to provide an adjustable inking roller that may be 45 variously positioned to accord with a given position of the stamp.

The invention also has for an important object to provide a chute associated with an element adapted to constitute the leaf of an 50 adding machine and having means thereon to close the chute and constitute an extension of the leaf when the indorsing attachment is not in use.

The invention also has for an object to 55 provide an indorsing machine improved in

various particulars with a view to promote accuracy of operation, facility of adjustment and control, and comprising appurtenances whereby the machine will be fully equipped to promote convenience and efficiency.

60 The nature of the invention and the advantages of the important structural features characterizing the preferred embodiment will more clearly appear as the description proceeds.

65 Reference is to be had to the accompanying drawings forming a part of this specification in which similar reference characters indicate corresponding parts in all the views.

70 Figure 1 is a front elevation of an indorsing machine embodying my invention showing the same applied to an adding machine;

Fig. 2 is a fragmentary side view.

75 Fig. 3 is a detail in transverse vertical section on the line 3—3, Fig. 1;

Fig. 4 is a longitudinal vertical section on an enlarged scale, the section being taken on the line 4—4, Fig. 1;

80 Fig. 4^a is a view similar to Fig. 4 but on a smaller scale and illustrating certain features of the invention in the preferred form;

Fig. 5 is a fragmentary longitudinal section through one of the bearings of the 85 rollers;

Fig. 6 is a section on the line 6—6, Fig. 8;

Fig. 7 is an end view of the rollers;

Fig. 8 is a fragmentary front elevation of one of the rollers;

Fig. 9 is a detail view showing a portion 90 of the drive shaft of the machine and a clutch associated therewith.

My improved indorsing machine is adapted to be secured to adding machines of known make to constitute an attachment 95 thereto and before giving a detail description of the parts, I wish to say that the chute through which the checks are fed to the rollers to be stamped by the latter, preferably is associated with a leaf member or table 100 adapted to constitute the leaf of an adding machine when the indorsing attachment is applied thereto, the said leaf and chute being formed as a part of my attachment in its preferred form is illustrated in Fig. 4^a. 105 The chute and leaf in the form illustrated in Figs. 1 and 4 contemplates the permanent attachment of the leaf to the adding machine or the modification of the leaf of known adding machines to constitute also 110

the rear wall of the chute when my attachment is applied to the adding machine.

Referring to Figs. 1 and 4 the numeral 10 designates generally the chute. To secure the attachment to an adding machine A, I provide an upper clamp 11 and a lower clamp 12, these being fixedly secured in any suitable manner to my indorsing attachment and adapted to embrace the adding machine. 10 The upper brace 11 has at the outer end thereof a member 13 at right angles to engage one side surface of the adding machine, and at the opposite side of the adding machine, said brace has a rearwardly extending member 14, the rear end of which has the lateral right angle bend as indicated at 15, Fig. 4, to engage the adding machine at the front. Each clamp is formed in adjustable sections to adapt it to adding machines of 20 different sizes and also for the purpose of producing a tight clamping action. As seen in Fig. 1, that member 16 of the upper clamp 11 which is secured to the chute 10 has a slot and pin connection with a relatively sliding section 17, there being slots 18 in the section 17 and studs 19 on the section 16, said studs being threaded to receive knurled nuts 20, or the like. Similarly, the lower clamp 12 has one section 21 fixedly secured 25 to my attachment while a sliding section 22 has a slot and pin connection with the section 21, the section 22 having slots 23 and the section 21 having threaded studs 24 receiving nuts 25. The outer end 26 of the section 22 has a right angle bend corresponding with the member 13 on the clamp 11 to engage a side of the adding machine. By the described arrangement my attachment may be quickly clamped to the adding machine. 40

The machine includes a suitable supporting base or frame, there being shown longitudinal side members 27 which also afford bearings for the rollers hereinafter described. Referring particularly to Figs. 1 and 4 the front 28 of the chute is suitably supported on the base frame, while the back 29 is made in the form of a downwardly inclined extension of a leaf 30 secured to the adding machine and corresponding with a similar leaf found in adding machines of different makes. Below the chute I provide a pair of rollers 31, 32, so that a check instead of being laid on the leaf 30 may be moved along the same to drop through the chute to the rollers to receive a stamped indorsement by the latter as presently described. In order that, when the indorsing rollers are not to be used, the chute may be closed, I provide a slide 33 on the under side of the leaf 30 and movable in suitable keepers or guides 34, said slide having a handle 35 at one end and the opposite end having a downwardly turned flange or stop 36 to engage the adjacent keeper 34 and limit the

rearward movement of the slide. The slide may be moved forwardly through a slot 37 at the upper end of the wall 29 whereby the slide will extend across the chute and constitute an extension of the leaf 30. 70

In Fig. 4^a which represents the attachment equipped complete with its own leaf and chute members, 10^a designates the chute, 28^a the front thereof, and 29^a the rear wall which is a part of the chute and in fixed relation to the front 28^a, and the sides being suitably supported on the base which in this form of the invention includes the side members 27 as previously described. The leaf 30^a is integral with the rear wall 29^a and is 80 equipped with the slide 33^a corresponding with the slide 33 and movable through a slot 37^a corresponding with the slot 37. With this form of the invention my indorsing machine when secured to the adding machine 85 A as an attachment to the latter, provides its own leaf and complete chute. 75

The roller 31 is provided with a rubber stamp 38 which has a curved surface concentric with the roller 31 but of slightly 90 greater radius to insure a proper impression by co-action with the roller 32. The back of the stamp 38 has a dove-tail rib 39 which is received in a longitudinal dove-tail groove 41 in the roller 31, and in said groove resilient metallic strips 40 are arranged at each side to effectively engage the rib 39 and at the same time permit a longitudinal movement of the stamp or its removal by squeezing the ends thereof. The stamp is 100 adapted thereby to be positioned variously along the roller to produce the indorsement at the proper location on the check. As the stamp occupies a comparatively small portion of the roller surface I provide resilient 105 dummies or filler blocks 42 having dove-tail ribs at the back thereof, the same as the stamp 38 to be received in the groove 41 between the resilient friction plates 40. Thus, the filler blocks may be placed one 110 at each side of the stamp or if the position of the stamp requires it, both the filler blocks may be placed at either side of the stamp, thereby steadyng the roller and maintaining it in proper relation to the co-acting 115 roller 32.

The roller 31 is mounted on a shaft 43 and the roller 32 on a shaft 44. On the rollers at one end intermeshing pinions 45 are provided to insure the turning of the 120 rollers 31, 32 in unison. Since any approved bearing may be employed for the shaft 43, I have conventionally shown the same turning in the side frames 27. As will be understood from Fig. 5, the shaft 44 is 125 received at each end in a V-shaped depression formed in a bearing block 46 which is slidable in a slot 47, said block being subject to the pressure of a compression spring 48 abutting at one end against the block 46 130

and at its opposite end against the end of the slot 47. Thus the roller 32 is yieldingly maintained to exert an even pressure against the roller 31.

5 On the shaft 43 at one end is a fixed clutch member 49 and adapted to be engaged by a mating clutch element 50 on the drive shaft 51 which is supported in bearings 52 on upright members 53 carried by the clamp sections 22. Surrounding the shaft between the bearings 52 is a housing 54 fixed to said bearings. On the outer end of the shaft 51 is a pinion 55 which is engaged by a rack bar 56, said rack bar being pivotally secured at one end to the crank handle B of the adding machine, whereby the operation of said handle in a forward direction will cause the rack bar to turn the pinion 55 one complete revolution, thereby turning the shaft 51 and the roller 31. In order that the rollers may not be given a retrograde movement by the rack bar 56 moving rearwardly, the clutch elements 49, 50 are of the one-tooth type, thereby having a single point engagement. The clutch element 50 is slideable on the shaft 51 and is held in engagement with the section 49 by a spring 50^a on the said shaft. A pin 50^b on the shaft is received in a slot 50^b in the clutch section 50 to turn the latter but to permit it to move axially on the shaft against the pressure of the spring 50^a. By the described arrangement, a forward stroke of the rack 56 and a consequent forward turning of the shaft 51 will turn the clutch section 49 and the roller shaft 43 a complete revolution, but upon a reverse movement of the rack 56 the clutch section 50 may turn relatively to the section 49, and 40 to prevent the clutch section 49 and the roller shaft 43 from turning backward with the clutch section 50, I provide stop means to engage said roller as hereinafter described. The rack 56 moves in a saddle 57 which is supported on the shaft 51 and may have a limited swinging movement thereon as required by the movements of said rack bar. Guide rollers 58 on the saddle engage the back of the rack bar as indicated in 45 Figs. 2 and 3.

An inking roller 59 is provided and is adjustably mounted on a rod 60 having suitable support at its ends as at 61 on frame members. The roller may be positioned variously along the rod 60 to suit the position of the stamp 38 and secured by a set screw 62.

For the purpose of insuring that the check dropping from the chute to the rollers will be firmly gripped by the latter and caused to pass therethrough, I produce cutouts or depressed surfaces 63 in the rollers so that gripping shoulders are thus provided to positively take hold of the check 65 so that in the turning of the rollers the

check will positively be drawn therethrough. It is important that the depressed surfaces 63 be maintained in proper register as the rollers turn and this is provided for by the means that prevent the retrograde movement of the rollers, said means consisting in the illustrated example of a stud 64 projecting from an end of the roller 31 as seen in Figs. 6 and 8 and adapted to be engaged by the free end of a spring 65 which is suitably fastened as at 66, 67 to the adjacent frame member 27. Moreover, there is a spring plate 68 secured to said member 27 to be engaged by the stud 64 in the turning of the rollers 31. The positions and arrangement of the springs 65, 68 are such that both springs will yield to the stud 64 as the roller 31 rotates forwardly and thereby permit the stud to pass the springs. The reverse movement 85 of the rack 56, however, occurs when the stud 64 has just passed the spring 68 and engaged the spring 65. Upon the roller 31 starting to reverse, the stud 64 will be engaged by the spring 68 and the movement 90 of the roller thereby arrested, thus positioning the rollers with the opposed depressed surfaces 63 opposite and upwardly disposed toward the chute to receive the check from the latter. 95

The checks discharged from the rollers 31, 32 after being indorsed are received in a basket 69 beneath the base frame and supported on the latter, the basket is hinged at one end as at 70 to a transverse frame member 71 at the inline 72. The opposite end of the basket 69 has a spring latch 73 adapted to resiliently engage a catch 74, the arrangement permitting the basket to be readily dropped and permitted to swing on 105 its hinges for the ready removal of the checks.

I wish to state in conclusion that although the illustrated examples constitute practical embodiments of my invention, I do not limit myself strictly to the mechanical details herein illustrated, since manifestly the same can be considerably varied without departure from the spirit of the invention as defined in the appended claims. 110

Having thus described my invention I claim as new, and desire to secure by Letters Patent:

1. An indorsing machine of the class described, comprising rotary indorsing means, drive means therefor including a drive shaft extending laterally at a side of the machine, clamp means secured to the indorsing machine and extending laterally therefrom at the same side as the drive shaft, said clamp means having a member to engage an adding machine along the side thereof adjacent to the indorsing machine, the said member terminating in a lateral bend to engage the adding machine at the front, the clamp 120

means including also a member to range across the adding machine at the back and terminating in a forwardly disposed member to engage the opposite side of the adding machine from the first-mentioned member, the clamp means being adjustable to conform to adding machines of different sizes, and actuating means to turn the said drive shaft by a movement of the crank arm 10 of the adding machine when said clamp is in position on the adding machine and with the actuating means connected with the said crank arm.

2. An indorsing machine of the class described comprising rotary indorsing means, drive means therefor including a drive shaft extending laterally at a side of the machine, clamp means secured to the indorsing machine and extending laterally therefrom at 20 the same side as the drive shaft, said clamp means including upper and lower elements adapted to engage the adding machine, bearings for said shaft, said bearings being carried by the lower clamp means, and means to actuate said shaft by the crank arm of the adding machine when the clamps are secured in position thereon.

3. An indorsing machine of the class de-

scribed, comprising rotary indorsing means, drive means therefor, including a drive shaft formed in sections, clutch elements on said shaft sections, the clutch elements having a single tooth engagement to permit a reverse movement of one relatively to the other through a complete revolution, and stop means to arrest the indorsing means and prevent retrograde movement thereof, said stop means including a member turning with the indorsing means, a spring yieldable to the said member, and a second spring 40 yieldable to a movement of said member in one direction acting to arrest reverse movement thereof, said member being adapted to be accommodated between the two springs.

4. An indorsing machine of the class described, including rotary indorsing means, means to turn the indorsing means, a chute supported on the machine above the rollers to direct checks to the latter, a leaf at the top of the chute and leading to one wall 50 thereof, and a slide beneath the said leaf and movable across the chute to cut off the latter and constitute an extension of the leaf.

RUDOLPH H. GLADWILL.
